M. HERSKOVITZ

ELECTRIC SOCKET STRUCTURE

Original Filed May 23, 1919

Fig. 1.

Fig. 2.

Inventor:

*Max Herskovitz,
Byzynski, S. Critten and Hills,
Atty.*

UNITED STATES PATENT OFFICE.

MAX HERSKOVITZ, OF CHICAGO, ILLINOIS; WILLIAM HERSKOVITZ (NOW BY JUDICIAL CHANGE OF NAME WILLIAM HERST) AND CHARLES WEINFELD, EXECUTORS OF SAID MAX HERSKOVITZ, DECEASED.

ELECTRIC-SOCKET STRUCTURE.

Original application filed May 23, 1919, Serial No. 299,198. Divided and this application filed January 5, 1924. Serial No. 684,646.

My invention relates generally to structures for housing the threaded contact shells and the center contacts for electrical connection with electric lamps and maintaining the same in fixed position on a support, certain of the uses to which the invention may be placed being in connection with ceiling lights and outlet bases, though as will be readily understood from the following, it may be put to other uses, the present application being a division of my pending application for United States Letters Patent Serial No. 299,198, filed May 23, 1919.

My primary object is to provide a novel, simple and inexpensive construction, of the general character above referred to. A further object is to provide a construction which, in one of its forms, is adapted to be supported in a number of different ways, as desired, and preferably form a support for a globe-carrying ceiling-band.

Referring to the accompanying drawing:—

Figure 1 is a view in sectional elevation of a portion of a ceiling containing an outlet-box and with which is associated an electric socket structure constructed in accordance with my invention and supporting a globe-supporting ceiling-band; and Figure 2, a perspective view of the housing structure of Fig. 1.

The socket structure illustrated comprises a hollow, cup-shaped member 10, open at its lower end and containing a screw-threaded aperture 11 at its opposite end, the wall of the member 10 adjacent the upper end of this member containing apertures 12. The member 10 slightly below the openings 12 is equipped at its opposite sides with outwardly-extending wings 13 containing elongated slots 14 between their ends and adjacent their outer ends threaded openings 15. The portion 10 houses the electrical screw-shell 16, which carries a disk 17 of insulating material equipped with a center contact 18, a lining 19 of insulating material being interposed between the member 10 and the shell 16. The shell 16 is indented as represented at 20, to interlock with the lining 19 and project a portion of the latter into an opening 21 in the member 10 to prevent rotation of the shell 16 in the member 10.

In the particular arrangement illustrated,

the device just described is shown as provided for co-operation with an outlet-box 22 located in an opening in a ceiling represented at 23. Outlet boxes, as commonly provided, are formed with a separate plate 24 screwed in place against the underside of the top plate of the box 22, as by the screws 25, and carrying a threaded nipple 26. This nipple 26 has preferably screwed thereon an extension piece 27, presenting the threaded extremity 28 upon which the member 10 is screwed at its threaded part 11 for securing the member 10 in place, the electric-current-conducting wires which extend into the box 22 extending through the opening 12 and being connected with the contacts 16 and 18 of the socket. The wings 13 in the particular case illustrated support a globe-supporting band 29, which is secured in place, as by the screws 30, screwing through an annular flange 31 of the band adjacent the ceiling and into the threaded apertures 15, the globe supported by the band 29 being represented at 32.

If desired, screws or nails (not shown) may be located in the slots 14 and extend into the ceiling 23, and while this manner of fastening the socket structure in place 80 may supplement the threaded connection of the member 10 with the outlet-box as stated, the slots 14 are preferably used only when direct connection between the member 10 and the outlet-box is not provided.

The wings 13 which may be made integrally with the housing 10 or as parts separate therefrom and secured together in any suitable way, may be rigid or of a character adapting them to be bent, in which latter 90 case the wings may be bent to adapt the device, to the best advantage, to different conditions presented in the installing of the same. Furthermore if desired, and particularly where a connection between the housing 10 and a nipple-equipped plate in the outlet-box is not provided, the upper end of the housing 10 may be left entirely open.

It will be readily understood from the foregoing that a structure embodying my 100 invention is simple and rigid and very inexpensive to manufacture.

While I have disclosed certain embodiments of my invention, I do not wish to be

understood as intending to limit it thereto as the same may be variously modified and altered without departing from the spirit of my invention, it being my intention to claim my invention as fully and completely as the prior state of the art will permit.

What I claim as new, and desire to secure by Letters Patent is:

1. In a socket structure, the combination 10 of a cup-shaped member containing electrical contacts for an electric lamp inserted into the open end of said member, said member presenting at one end a portion at which said member attaches to a support 15 and apertured at one side of said portion for receiving electric wires connected with said contacts, and arms extending outwardly from said member, said arms containing threaded apertures adjacent their outer ends 20 and other apertures between their ends, the

latter for receiving devices for securing the socket structure in place.

2. In a socket structure, the combination of a cup-shaped member containing electrical contacts for an electric lamp inserted into the open end of said member, said member presenting at one end an internally-threaded aperture at which it is adapted to attach to a support, said member being apertured at opposite sides of said threaded aperture for receiving electric wires connected with said contacts, and arms extending outwardly from said member, said arms containing threaded openings adjacent their outer ends and containing other openings between their ends, the latter for receiving devices for securing the socket structure in place.

MAX HERSKOVITZ.
